AUTOMATICALLY OPERABLE SNAP-ACTING SWITCH

Earnest J. Dillman, Detroit, Mich., assignor to
Detroit Lubricator Company, Detroit, Mich., a
corporation of Michigan

Application June 21, 1947, Serial No. 756,265

31 Claims. (Cl. 200—83)

1

This invention relates to new and useful improvements in automatically operable snap acting devices.

An object of this invention is to provide an improved snap switch which is automatically operable upon rise or fall of a physical condition above or below predetermined limits.

Another object of this invention is to provide an improved thrust linkage for an automatically operable snap acting device.

Another object of this invention is to provide an improved carrier mechanism for the switch contacts of a snap switch whereby vibration and "chatter" upon opening or closing motion may be substantially reduced or eliminated.

Another object of this invention is to provide an improved snap acting mechanism having an improved thrust linkage and being automatically responsive to changes in conditions affecting the operating mechanism.

Other objects of this invention will become apparent from time to time through the specification and claims as hereinafter recited.

This invention consists of the new and improved construction and combination of parts to be more fully described hereinafter and the novelty of which will be particularly pointed out and distinctly claimed.

In the accompanying drawings, to be taken as a part of this specification, there are clearly and fully illustrated a number of preferred embodiments of this invention, in which drawings:

Figure 1 is a plan view of a device embodying this invention as applied to a pressure operated snap switch and having the casing cover member removed to show internal construction.

Fig. 2 is a sectional view taken along the line 2—2 of Fig. 1 having the cover member in place but having the insulating member end wall removed.

Fig. 3 is an enlarged sectional view taken along the line 3—3 of Fig. 2.

Fig. 4 is a sectional view taken along the line 4—4 of Fig. 3.

Fig. 5 is a detail sectional view taken along the line 5—5 of Fig. 2.

Fig. 6 is an enlarged sectional view taken along the line 6—6 of Fig. 1 but having the cover member in place.

Fig. 7 is a view in side elevation and partly in section showing a modification of the invention operable by expansion of a thermo-expansive pellet.

Fig. 8 is a view in vertical section on the line 8—8 of Fig. 9 and showing another modification

2

of the invention operable by direct fluid expansion,

Fig. 9 is a detail sectional view of the last mentioned modification and is taken along the line 9—9 of Fig. 8.

Fig. 10 is a detail sectional view of the last named modification and is taken along the line 10—10 of Fig. 9, and

Fig. 11 is a view in vertical section showing another modification of the invention operable by a thermo-sensitive bellows and applicable for use as a room thermostat.

Referring to the drawings by characters of reference in Figs. 1 to 6 there is an automatically operable snap switch 1 having an outer casing 2 with a cover member 3 secured thereto by screws 4. An inner casing 5 carries the main switch mechanism and is substantially covered along its bottom and end walls by a U shaped member 6 of an insulating material. The inner casing 5 and the U shaped insulating member 6 are secured each to each and to the bottom wall of the outer casing 2 by a plurality of screws or bolts 6a. In the switch mechanism there are two pairs of electrical contacts, two of the contacts 7 being movable and the other two contacts 8 being fixed and carried by abutments 9 projecting downward from the upper wall 10 of the inner casing 5. The movable contacts 7 are carried by a lever 11 which is bifurcated at one end and trifurcated at the other end. The lever 11 is fabricated of a non-metallic insulating material, such as a laminated phenolic plastic, and has a metal U shaped flanged member 12 partially covering and enclosing the bifurcated end. The trifurcated end portion of the lever 11 consists of two outer prongs 13 and an inner prong 14. A U shaped member 15 of hard resilient highly conducting material such as beryllium copper alloy is carried by the upper side of the lever 11 and affixed thereto by two rivets 16 and has its parallel legs 17 extending longitudinally of the lever 11 from the outer prongs 13 of the trifurcated end portion. The legs 17 of the U shaped member 15 carry the movable contacts 7 and each terminates in a tongue portion 18. Positioned on and carried by the underside of the lever 11 is another U shaped member 19 affixed thereto by the rivets 16. The U shaped member 19 has two parallel leg portions 20 extending longitudinally of the lever 11 and terminating in up-turned end portions 21. The legs 20 are offset from the lever 11 and inherently stressed downward from the lever 11. The up-turned end portions 21 have apertures 22 there-

through which are operable to receive the tongue portions 18 of the legs 17 of the U shaped member 15. The parallel legs 20 of the U shaped member 18 have holes 23 therethrough extending into the outer prongs 13 of the lever 11 and operable to receive an adjustment member or screw 24 positioned therein. The adjustment screw 24 is operable upon movement to permit movement of the legs 20 downward thus tensioning the contact carrying legs 17. The lever 11 is pivoted on two fulcrum pins 25 extending through the wall of the inner casing 5 into the downturned side portions of the flanged member 12. Adjacent the free end portion of the lever 11 there is a bent arm portion or bracket member 26 which is carried by the upper wall portion 10 and affixed thereto by two rivets 27. The bracket 26 has an aperture 28 through its lower extremity and is operable to receive therein the tongue portion 29 extending from the center prong 14 of the lever 11. The aperture 28 in cooperation with the tongue portion 29 functions as a stop member limiting the extent of travel of the lever 11. A magnetic armature 30 is carried by the center prong 14 of the lever 11 and affixed thereto. Carried by the upper wall 10 is a magnet 31 secured by a screw or bolt 32 to a screw-threaded member 33. The screw-threaded member 33 is threadedly connected to a drilled and tapped portion 34 of an adjustment member 35 having an annular flange portion 36. The adjustment member 35 is screw-threadedly connected to a knob 37 by which upward and downward adjustment of the magnet 31 may be effected. A leaf spring 38 is mounted against the underside of the upper wall 10 by a rivet 39 and has a bifurcated end portion 40 straddling the adjustment member 35 and engaging the upper face of the annular flange 36 and is operable to prevent rotation of the adjustment member 35 and the magnet 31 when the knob 37 is rotated and is further operable to hold the adjustment member 35 and magnet 31 in position as determined by the knob 37. The knob 37 seats in and is rigid with a calibrated dial member 37a which seats against the upper face of the upper wall 10 and is limited in rotary movement by cooperation with a stop plate member 37b secured to the upper wall 10 by the rivets 21. The switch carrying abutment 9 is screw-threadedly connected to a bracket or molded insert 41 (see Fig. 5) in the upper wall of the cover member 19. Secured to the upper wall 10 by each of the molded insert members 41 is the flanged edge portion 42 of a shield member 43 made of electrical insulating material such as a laminated phenolic plastic. Also secured to the upper wall and by the insert member 41 is a flanged bracket member 44 of a conducting material operable to receive a screw or bolt connection 45 for connecting the wire of an electrical circuit to the contact 8. The upper wall member 10 is secured to the inner casing 5 by screws 46 affixing the wall 10 to a turned-in flange portion 47 of the casing 5. Two of the screws 46 also function to secure an extra cover member 48, of a thin insulating material to the upper wall member 10 in overlying relation to the terminals 45.

Positioned in the aperture 49 formed by the bifurcated end portion of the lever 11 and the U shaped flange member 12 is a swivel member 50 pivotally mounted on a fulcrum pin 51 extending laterally across the aperture 49 between the opposite walls of the downturned inner flange portion 52 of the flange member 12. The swivel

member 50 has an annular shoulder portion 53 around its upper edge and a similar portion 54 around its lower edge. The swivel member 50 also has a conical depression 55 centrally located in its lower face. A helical spring 56 is seated in the annular shoulder portion 53 of the swivel member 50 and is operable to urge the swivel member 50 downward thus rotating the lever 11 on its fulcrum. A frusto-conical cylindrical member 57 having an annular flange portion 58 and a longitudinal guideway 59 is positioned on the opposite end of the spring 56 from the swivel member 50. An adjustable threaded member 59a is screw threaded into a sleeve member 60 in the upper wall 10 of the casing 5 and has a screw threaded bore 61 extending longitudinally therethrough. An adjustable screw 62 having a cylindrical end portion 63 engages the member 57 in the guideway 59 and is operable to determine the compression of the spring 56. Carried by and affixed to the upper end of the adjustment member 59a is a knob portion 64 having a calibrated dial plate 65 engageable with an indicator 66 carried by a bracket or angle member 67 secured to the upper wall 10 by rivets 68. The indicator 66 is operable to limit rotary movement of the knob 64 by engagement with stop portions of the dial plate 65.

The casing 5 has a lower wall 69 having an aperture 70 extending therethrough and through the lower wall 71 of the outer casing 2. Positioned through the aperture 70 and secured to the lower wall 69 of the inner casing 5 is a hollow connection member 72 having an internally threaded end portion 73 to receive a pressure line or conduit. Positioned in the upper end portion of the connection member 72 is a wall member 74 having a down-turned flange portion 75 secured to the upper end portion as at 76. A screw threaded member 77 is adjustably positioned in the upper extremity of the threaded portion 73 of the connection member 72 and forms the bottom wall of a chamber 78. The wall member 74 has an aperture 79 interconnecting the chamber 78 and the interior of the casing 5 and has a plunger member 80 positioned therein. The plunger member 80 is substantially cylindrical in form, having a hollow portion extending partially longitudinally therethrough and having a flanged portion 81 at its lower extremity and terminating in an extended conical tip 82 at its upper extremity. The conical tip 82 is positioned in engagement with the conical recess 55 in the swivel member 50. A cylindrical metal bellows or pressure responsive member 83 is sealed to the wall 74 in the aperture 79, surrounds the plunger 80 and is sealed to the flanged portion 81. A helical spring 84 is positioned in the hollow portion 85 of the plunger 80 and is compressed between the upper wall 86 of the hollow portion 85 and the upper face of the screw threaded member 77 which may be provided with a lock nut. The screw threaded member 77 has an aperture 86a interconnecting the threaded end portion 73 and the chamber portion 78 of the connection member 72 and is operable to permit pressure such as from a steam line to enter the chamber 78 and actuate the bellows 83 and plunger 80.

In operation this form of the invention functions as follows:

In its initial state the switch contacts 7 and 8 are normally open, the spring 56 urging the lever 11 toward its open position and the inherent resilience of the bellows 83 and the spring 84 being

operative to resist this movement by the spring 56. When gaseous pressure such as from a steam line is supplied to the chamber 78 of the connection member 72 the bellows 83 is compressed and the plunger moves longitudinally upward against the swivel member 50 thus causing the lever 11 to rotate toward switch closed position. When the pressure has caused the plunger 80 to move the lever 11 upward a distance sufficient to permit an appreciable attraction between the magnet 31 and the armature 30 the attractive force of the magnet 31 acting in cooperation with the pressure operated bellows 83 will be sufficient to overcome the force of the upper spring 56 and cause the switch contacts 7 and 8 to close with a snap action. Conversely, when the pressure operating the switch is decreasing, the magnet 31 will hold the contacts closed after the pressure operating the bellows 83 is no longer strong enough of itself to resist movement by the spring 56 and when the combined force exerted by the pressure on the bellows 83 and the magnetic attraction between the magnet 31 and the armature 30 becomes less than the force exerted by the spring 56 the contacts 7 and 8 will then open with a snap action. It should be noted that the bracket member 26 and its aperture 28 cooperating with the tongue portion 29 of the lever 11 will prevent any further application of force upon the contacts 7 and 8 when in closed position and functions as a limit stop for opening and closing movement of the lever 11. When the switch contacts 7 are in open position the resilient member 17 is tensioned by the tongue portion 18 which extends through the aperture 21 of the other U shaped member 19. When the switch contact 7 closes against the contact 8, the tongue portion 18 is moved out of engagement with the member 20 and the contact 7 is tensioned against the contact 8 by the resilience of the arm 17 of the U shaped member 15 functioning as a cantilever spring. Upon opening movement the upturned flange portion 21 of the U shaped member 20 again engages the tongue portion 18 and tensions the resilient arm 17 thus preventing vibration or "chatter" on this opening movement. The amount of tension desired in the contact-carrying arm 17 may be adjusted by the screw 24 by which the arm 20 of the U shaped member 19 may be permitted to move downward. The air gap distance between the magnet 31 and the armature 30 when the switch contacts are closed may be adjusted by the knob 37; this adjustment of the magnetic air gap distance will determine the amount of travel by the lever 11 necessary to cause the switch to close with a snap action. This adjustment of magnetic air gap distance has the further function of determining the differential of pressure between that required to open or to close the switch. The magnet 31 has the additional function of maintaining the switch contacts tensioned against each other in closed position. The compression of the spring 56 may be adjusted by the knob 64 thus determining the force required in opposition to the spring 56 to close the switch contacts 7 and 8. The screw threaded member 11 bearing against the spring 84 is operable upon adjustment to determine the force exerted by the spring 84 and the bellows 83 against the upper spring 56. It should be noted that the operation of this pressure operated switch is especially adaptable for use as an alarm switch for registering the effect of excessive rise of pressure in a gas line or more especially in a steam line.

In the form of the invention shown in Fig. 7 there is a snap switch which is adapted to respond to changes of temperature. The essential elements of this switch (e. g. the lever, resilient 5 contact carrying arm, the swivel member, the spring 56 bearing against the swivel member etc.) are common to all forms of the invention shown throughout the various drawings and all common parts are given the same reference numerals as 10 in the principal form of the invention illustrated in Figs. 1 to 6. The principal difference between the principal form of this invention and that shown in Fig. 7 is that the modification shown in Fig. 7 is adapted to respond to a thermal sensitive element. There is a connection member 87 positioned through the lower wall 69 of the casing 5 which corresponds to the member 72 in the principal form of the invention. The connection member 87 is externally threaded as at 88 to provide 15 a screw connection for mounting to the object to be controlled (such as a hot water or steam boiler). The member 87 has a longitudinal passageway therethrough of a large bore 89 at its upper end, a smaller bore 90 at its lower end and a small passageway 91 interconnecting the bores 89 and 90. Extending from the lower bore portion 90 is a conduit or supporting member 92 having therein a cylindrical member 93 with a flange portion 94 at its lower end. The 20 cylindrical member 93 has an internal bore 95 with a plug member 96 of a rubber or rubber-like material. Positioned below the flange 94 is a cup-shaped member 97 having a flange portion 98. The cup-shaped member 97 is joined by 25 its flange portion 98 to the flange portion 94 and held in position by an annular flanged member 99 and having a diaphragm member 100 positioned between the flanges 94 and 98 and closing the open end of the member 97 just below the plug member 96. The diaphragm member 100 and the cup-shaped member 97 form a closed chamber having a thermal responsive material 101 therein. The thermal responsive material 101 is preferably 30 formed of a mixture of waxes which have a high rate of expansion when changing from the solid to liquid state or may be of a composition such as is disclosed by Patent 2,259,846 issued to Sergius Vernet. Positioned in the bore 95 of the cylindrical member 93 and seating on the plug 35 member 96 is a piston 102 which has a flanged stop portion 103 and bears against a plunger 104 which extends through the longitudinal passageway or bores 89 and 90 and is guided in and through the bore 91 and terminates in an annular shoulder portion 105. Seated on the annular shoulder portion 105 is a flanged disc member 106 having a helical spring 107 seating thereagainst, the spring 107 seating at its other extremity on the annular shoulder portion 54 of the swivel member 50. Other changes from the principal form 40 of the invention are only minor details of construction.

In this form of the invention there is no outer casing 2 but the inner casing 5 is closed at its end 45 portions by a U shaped member 108 held in position by screws or bolts 109. The magnet 31 is carried directly by a screw-threaded member or bolt 110 having a stop nut 111 and adjustable by use of a screwdriver or other means instead of a 50 knob 37. Similarly the adjustment of the compression of the spring 56 is effected by the screw member or bolt 62 instead of the knob 64 and has a stop nut 112 to secure the bolt 62 in position.

In operation this form of the invention functions as follows:

When the temperature of the thermal responsive material 161 is increased, the material expands and exerts force through the diaphragm 100 and plug 96 against the piston 102 and the plunger 104. As the plunger 104 moves upward, this movement is transmitted through the spring 107 to the swivel member 50 causing the lever 11 to be rotated towards contact closed position. When the lever 11 is rotated a sufficient distance that the combined force of the magnet 31 acting upon the armature 30 and the force of the spring 107 is greater than the force exerted by the spring 56 the switch will snap closed. Similarly upon fall of temperature the magnet 31 will hold the switch contacts 7 and 8 closed until the combined force of the magnet 31 and the spring 107 become less than the force exerted by the spring 56. The attraction of the magnet 31 as above described will determine the differential between the temperatures required to open or to close the switch. As in the main form of the invention, the switch contact carrying arms 17 are tensioned by the member 20 so as to prevent vibration or chatter upon opening and closing the switch contacts.

It should be noted that in all forms of this invention heretofore and hereafter described the switch can be made to operate in reverse by moving the fulcrum point for the lever 11 to the opposite side of the fulcrum point for the swivel member 50 than that described so that a rise of temperature or pressure will cause the switch contacts to operate in a reverse direction from that shown. It should be further noted that for the magnet to be able to pull the contacts closed with a snap action there must not be an appreciable decrease in force applied in opposition to the spring 56 upon sudden movement of the lever 11 since the magnet is not sufficiently strong to hold the contacts closed against the force of the spring 56. If the means transmitting the force to the swivel member 50 in opposition to the spring 56 is a solid incompressible means then the force applied to that means must be compressible for otherwise a slight movement of the force transmitting means would cause a very great reduction in pressure applied thereto. This last assertion is readily illustrated by a comparison of the functioning of the principal form of the invention with the application of gaseous pressure or with liquid pressure. If gaseous pressure is applied to the chamber 78 (see Fig. 6) and the switch contacts are moved towards closed position then the snap action movement of the lever 11 caused by the attractive force of the magnet 31 would not cause an appreciable reduction in pressure applied to the plunger 80. On the other hand, if liquid pressure were applied to this form of the invention there could never be a snap action because a very slight movement of the lever away from the plunger 80 would cause a reduction in pressure against the plunger 80 substantially to zero. Conversely it is seen that if the force actuating the lever in opposition to the spring 56 is of an incompressible type such as caused by liquid or solid expansion then the means transmitting that force must be compressible such as the spring 107 in Fig. 7. In this form as the temperature rises the thermal responsive material 161 expands providing an incompressible source of force for actuating the lever 11. This force is transmitted through the spring 107 to the swivel member 50 so that when the lever 11 moves within the force of attraction of the magnet 31 the slight closing movement of the switch will not cause an appreciable reduction

in the compressive force exerted by the spring 107. It should be further noted that in both basic forms of this invention the increase of attractive force of the magnet 31 upon closing movement of the switch contacts must be greater than the decrease of force applied in opposition to the spring 56 when the magnetic air gap distance is sufficiently small to permit the magnetic force in cooperation with opposing force to overcome the force of the spring 56.

In the form of the invention shown in Figs. 8, 9 and 10, the switch mechanism is essentially that shown and described in Fig. 7 but adapted for response to fluid expansion (either expansion by pressure or thermal expansion) and the modifications from the form shown in Fig. 7 are only slight.

As pointed out heretofore, all parts which are common are given common reference characters and function as heretofore described. In the form shown in Fig. 8 there is an outer casing 2 enclosing the switch mechanism and inner casing 5 which is secured thereto by a screw or bolt member 113, the outer casing 2 having a cover member 3 secured thereto by screws or bolt members 4. There is an elongated connection member 114 which is externally threaded as at 115 for mounting and receives at its lower end a conduit 116 operable to transmit expansive force of a liquid to the responsive mechanism of the switch. There is a large bore portion 89 in the upper end of the connection member 114 and a smaller threaded bore portion 117 immediately therebelow which is operable to receive a threaded hollow cylindrical plug member 118. A small bore or longitudinal passageway 119 interconnects the end portion receiving the conduit 116 and the threaded bore portion 117. There is an expansive diaphragm or pressure responsive sealing member 120 of a rubber-like material which is sealed to an internal annular shoulder 121 by the threaded plug member 118 and is operable to form an expandible chamber 122 for receiving fluid under pressure from the conduit 116 and the passageway 119. Seating on its lower end on the sealing member 120 is a plunger 104 having an annular shoulder 105 with a flange disc member 106 seating thereon. A spring 107 is positioned between the flange disc member 106 and the annular shoulder 54 of the swivel member 50 and is operable to transmit thrust therebetween. There are some slight changes in the structure of the lever and switch mechanism which will be enumerated hereinafter. The lever 11 is fulcrumed on the fulcrum pin 123 (see Fig. 9) extending from wall to wall across the casing 5 and passing through an enlarged aperture 124 (see Fig. 8) in the swivel member 50. Other minor changes include the use of knobs and calibrated dials as in Figs. 1 to 6 on the screw mechanism for adjustment of magnetic gap and compression of the spring 56. In this form, however, the indicator 125 is located between the two knobs instead of between the spring adjustment knob and end of casing as in Fig. 3. The bracket stop member 26 is replaced by a cylindrical rod 126 having an annular groove 127 therein between the shoulders of which is positioned the tongue portion 29 of the lever 11. The shoulders of the groove 127 are operable as limit stops for limiting movement of the lever 11. Also in this form of the invention the contact carrying arms 17 are tensioned by the member 19 but the adjustment screw 24 has been eliminated so that there

is no adjustment of the amount of tension in the contact carrying arms.

In operation this form of the invention functions similarly to the form illustrated in Fig. 7 and by pressure transmitted through the conduit 116 and the passageway 119 to the chamber or space 122. This fluid under pressure being operable upon expansion or movement to move the plunger 104^a thus transmitting force or movement through the spring 107 to the lever 11 for moving the switch contacts 7 to closed position as shown. The adjustment of the magnet and of the spring 56 is by the knobs 37 and 64 respectively, these adjustments being operable to determine the pressure or amount of movement of fluid necessary to close said switch. As in the previous form there is an incompressible force transmitted through a compressible force transmitting means (the spring 107) and operable to move the lever 11; as pointed out heretofore the operation of an incompressible force through a compressible transmitting means or a compressible force through an incompressible transmitting means makes it possible to produce a sensitive switch mechanism that is snap acting.

In the form shown in Fig. 11 there is a modification of the principal form of the invention similar to that shown in Figs. 1 to 6 in which a pressure responsive bellows 128, which is similar to the responsive bellows 83 (shown in Fig. 6) but is completely enclosed and is responsive to changes in pressure caused by expansion and contraction of a thermal responsive gas or volatile liquid enclosed therearound. This form of the invention is adaptable particularly to use as a room thermostat. There is an outer casing 129 having a removable end wall 130 and cover plate 131. The end wall 130 is secured to the casing 129 by screws 132 and the cover member 131 is secured to the end wall 130 by a screw 133. The inner casing 5 is secured to and carried by the end wall 130. As heretofore pointed out the parts of this form of the invention which are common to the others are given the same reference characters and are assembled substantially as heretofore described. There is a plunger 80^a having a conical tip portion 82^a which bears against the conical depression 55 in the swivel member 50. The plunger 80^a is also surrounded by and fixed to the end wall of the pressure responsive bellows 128 as was the plunger 80 in Fig. 6. There is a cup-shaped member 134 enclosing the bellows 128 and closed by an end member 135 of a non-metallic material and having an aperture 136 therethrough for longitudinal movement of the plunger 80^a. An annular flange member 137 is sealed to the cup-shaped member 134 and to the bellows 128, the bellows 128 and cup-shaped member 134 enclosing a chamber portion 138 in which is contained the aforementioned thermal responsive gas or volatile liquid. The cup-shaped member 134, bellows 128, end member 135 and plunger 80^a are carried by the end wall member 130 and spaced therefrom by a plurality of posts 138^a. In this modification the adjustment of the magnet is by an adjustment screw or bolt 110 and lock nut 111 as was shown in Fig. 7. The essential difference in this form of the invention is the change in the mechanism for adjusting the tension of the spring 56 whereby the temperature at which the switch will respond may be more easily adjusted. There is a saddle shaped member 139 carried by the upper wall 10 and secured thereto by the screw or bolt 46 extending through the flange portion 140 and the wall portion 10

into the inturned flanged portion 41 of the side wall of the inner casing 5. There is a flange disc member 57 engaging the spring 56 as in the other forms of the invention but in this form the member 57 has a bore 141 passing centrally therethrough in which is positioned a cylindrical rod 142 along which the member 57 may have longitudinal movement, the rod 142 being secured to and carried by the saddle member 139. The saddle member 139 terminates at one end in a pair of projecting portions 143, only one being shown, each having a pointed portion 144 cooperatively engaging side edge projecting arms 145 from a lever 146 and functioning as a fulcrum point therefor. The lever 146 has an aperture 147 therethrough and spaced projecting portions 148 which engage the face of the disc member 57 and are operable upon movement to move the disc member 57 longitudinally along the rod 142 thereby adjusting the compression of the spring 56. Cooperable with the lever 146 there is a lever member 149 having a turned-down edge or flange portion 150 and fulcrumed on a pin 151 which is carried by the end wall 130. A screw threaded adjustment member 152 is screw threadedly positioned through and operable to move the lever 149 and has a knob portion 153 of a non-metallic material. The adjustment screw 152 is screw threadedly positioned through the lever 149 and bears against the end wall 130 and is operable upon rotary movement to move the lever 149 about its fulcrum 151. The screw 152 carries an indicator disc 153^a viewable through a window opening 153^b and having edge stops cooperable with a rotation limiting member 153^c. The levers 149 and 146 have slots or apertures 154 and 155 respectively through and between which is positioned a thrust rod 156 in the form of a channel member having tongue portions 157 and 158 extending through the aforementioned apertures and through an aperture 159 in the end wall 130 and operable to transmit thrust between the lever 149 and the lever 146. It should be noted then from the aforementioned construction that movement of the adjustment knob 153 will be transmitted through the lever 149 and the thrust rod 156 and the lever 146 to the spring 56 thereby controlling the compression of the spring 56 and determining the force required to open the switch which in this case would be the temperature to which this device would respond. In commercial applications the knob 153 and mechanism interconnected therewith would be calibrated for adjustment to room temperatures to which this thermostatic switch would respond. In all other features this device is substantially as described heretofore in the other forms.

In operation this form of the invention functions as a thermostat responsive to changes in room temperature. When the temperature in the chamber 138 increases, the pressure therein increases causing the bellows 128 to move the plunger 80^a against the opposition of the spring 56 thus causing the switch contacts to open (this form being as suggested heretofore in that the fulcrum point for the lever 11 is on the opposite side of the fulcrum point for the swivel member as compared to the other forms of this invention). When the temperature decreases, the bellows 128 will expand permitting the switch contacts to close with a snap action thus reenergizing the circuit and the heat unit controlled by this thermostat. For adjustment of temperature at which this device will respond, the movement of

the knob 153 will transmit movement through the levers 149, 146 and the thrust member 153 to the spring 56 thereby determining the compression of the spring 56 and the temperature at which this switch will respond. It should be noted that a feature common to all forms of the invention shown is the arrangement of the spring 56 relative to the opposing force on opposite side of the swivel member 50. In each of the forms of the invention the lever 11 is shiftable slightly on its fulcrum within the limits of the inner casing 5 and the opposing forces acting upon the swivel member 50 are diametrically opposed and substantially equal so that they function to keep the lever 11 centered on its fulcrum and thereby reduce the possibility of friction by the edges of the lever 11 against the side walls of the inner casing 5. It should be further noted that the form of transmitting force through one spring and a swivel member against an opposing spring to provide movement for a lever is not restricted to the opening and closing of switch contacts but could be used in many forms of control devices such as for the opening and closing of a valve stem operable by the lever 11.

What is claimed and is desired to be secured by Letters Patent of the United States is:

1. In a switch, a pair of switch contacts, one of said contacts being movable, the other of said contacts being fixed, a lever carrying said movable contact, stop means cooperable with said lever and operable to determine the limits of travel of said lever, said lever having an aperture through one end, a swivel member pivotally carried by said lever in said aperture, spring means engageable with said swivel member and operable to urge said lever in one direction, means alined with and engaging said swivel member in opposition to said spring means and operable to urge said lever in the opposite direction, and tensioned resilient means carried by said lever and carrying said movable contact so that said switch may open or close without appreciable vibration.

2. In an automatically operable snap switch, a pair of switch contacts, one of said contacts being movable, the other of said contacts being fixed, a lever carrying said movable contact, means operable to cause said lever to open and to close said switch with a snap action, stop means cooperable with said lever and operable to determine the limits of travel of said lever, said lever having an aperture through one end, a swivel member pivotally carried by said lever in said aperture, spring means engageable with said swivel member and operable to urge said lever in one direction, means alined with and engaging said swivel member in opposition to said spring means and operable to urge said lever in the opposite direction, and tensioned resilient means carried by said lever and carrying said movable contact so that said switch may open or close with a snap action without appreciable vibration.

3. In an automatically operable snap switch, a pair of switch contacts, one of said contacts being movable, the other of said contacts being fixed, a lever carrying said movable contact, means operable to cause said lever to open and to close said switch with a snap action, stop means cooperable with said lever and operable to determine the limits of travel of said lever, said lever having an aperture through one end, a swivel member pivotally carried by said lever in said aperture, spring means engageable with said

swivel member and operable to urge said lever in one direction, means alined with and engaging said swivel member in opposition to said spring means and operable to urge said lever in the opposite direction, tensioned resilient means carried by said lever and carrying said movable contact so that said switch may open or close with a snap action without appreciable vibration, and said first-named means being further operable to hold said resilient contact carrying means tensioned against said fixed contact when said switch is closed.

4. In an automatically operable snap switch, a pair of switch contacts, one of said contacts being movable, the other of said contacts being fixed, a lever carrying said movable contact, means at each side of said lever operable to support the lever's fulcrum, said lever being shiftable laterally on its fulcrum, means to cause said switch to open and to close with a snap action, said last-named means also functioning to hold said movable contact tensioned against said fixed contact when said switch is closed, spring means urging said lever in one direction, a second spring means operable to urge said lever in the opposite direction, automatically operable means for supplying force to said second-named spring means, and said first-named and said second spring means being alined with and diametrically opposed to each other thereby acting to center said lever on its fulcrum and thus reduce side friction between said lever and said supporting means.

5. In an automatically operable snap switch, a pair of switch contacts, one of said contacts being movable, the other of said contacts being fixed, a lever carrying said movable contact, means at each side of said lever operable to support the lever's fulcrum, said lever being shiftable slightly laterally on its fulcrum, means to cause said switch to open and to close with a snap action, said last-named means also functioning to hold said movable contact tensioned against said fixed contact when said switch is closed, spring means urging said lever in one direction, means responsive to the restricted movement of an incompressible fluid under pressure, a second spring means for transmitting force from said last-named means to said lever and acting in opposition to said first-named spring means, and said first-named and said second spring means being alined with and diametrically opposed to each other thereby acting to center said lever on its fulcrum and thus reduce side friction between said lever and said supporting means.

6. In an automatically operable snap switch, a pair of switch contacts, one of said contacts being movable, the other of said contacts being fixed, a lever carrying said movable contact, means at each side of said lever operable to support the lever's fulcrum, said lever being shiftable slightly laterally on its fulcrum, means to cause said switch to open and to close with a snap action, said last-named means also functioning to hold said movable contact tensioned against said fixed contact when said switch is closed, spring means urging said lever in one direction, means responsive to the pressure of a compressible fluid, a second spring means cooperable with said last-named means and acting therewith in opposition to said first-named spring means, said second spring means and said pressure responsive means being operable to urge said lever in the opposite direction; and said first-named spring means, and said second spring means and pressure re-

sponsive means, being alined with and diametrically opposed to each other thereby acting to center said lever on its fulcrum and thus reduce side friction between said lever and said supporting means.

7. In an automatically operable snap switch, a pair of switch contacts, one of said contacts being movable, the other of said contacts being fixed, a lever carrying said movable contact, means for supporting the fulcrum of said lever positioned to each side thereof, said lever being shiftable slightly laterally on its fulcrum, a magnetic armature carried by said lever, a magnet for attracting said armature and operable to cause said switch to open and to close with a snap action, said magnet also functioning to hold said movable contact tensioned against said fixed contact when said switch is closed, spring means urging said lever in one direction, means urging said lever in the opposite direction, said last-named means including means responsive to expansive movement of a liquid under pressure and including a second spring means, said second spring means being alined with and diametrically opposed to said first-named spring means thereby acting to center said lever on its fulcrum and thus reduce side friction between said lever and said supporting means, and means for adjusting the compression of said first-named spring means thereby to determine the condition to which said switch will respond.

8. In an automatically operable snap switch, a pair of switch contacts, one of said contacts being fixed, the other of said contacts being movable, a lever carrying said movable contact, an armature carried by said lever, a magnet for attracting said armature and operable to cause said switch to open and to close with a snap action, said magnet also functioning to hold said movable contact tensioned against said fixed contact when said switch is closed, a spring urging said lever in one direction, an adjustable abutment for adjusting the compression of said spring, a plunger bearing against said lever in opposition to said spring, a metal bellows surrounding said plunger and affixed to said plunger at one end, said bellows functioning as a spring in opposition to said first-named spring, a spring bearing against said plunger, an adjustable abutment for adjusting the compression of said second spring, said second spring being adjustable to determine the tension against said first spring, said plunger and bellows being responsive to the application of gaseous pressure thereto thereby to actuate said lever, and said first spring being adjustable to determine the pressure to which said switch will respond.

9. In an automatically operable snap switch, a pair of switch contacts, one of said contacts being fixed, the other of said contacts being movable, a lever carrying said movable contact, an armature carried by said lever, a magnet for attracting said armature and operable to cause said switch to open and to close with a snap action, said magnet also functioning to hold said movable contact tensioned against said fixed contact when said switch is closed, a spring urging said lever in one direction, an adjustable abutment for adjusting the compression of said spring, a second spring urging said lever in the opposite direction, said second spring being alined with and diametrically opposed to said first spring and of substantially the same strength as said first spring, liquid expansion responsive means for transmitting movement to said second spring

and said lever, a plunger operatively connecting said liquid expansion responsive means and said second spring, said liquid expansion responsive means being operative to actuate said lever, and said first spring being adjustable to determine the condition to which said switch will respond.

10. In an automatically operable snap switch, a pair of switch contacts, one of said contacts being fixed, the other of said contacts being movable, a lever carrying said movable contact, means operable to cause said switch to open and to close with a snap action, said means also functioning to hold said movable contact tensioned against said fixed contact when said switch is closed, a spring urging said lever in one direction, an adjustable abutment for adjusting the compression of said spring, a second spring urging said lever in the opposite direction, said second spring being alined with and diametrically opposed to said first spring and of substantially the same strength as said first spring, liquid expansion responsive means for transmitting movement to said second spring and said lever, a plunger operatively connecting said liquid expansion responsive means and said second spring, said liquid expansion responsive means being operative to actuate said lever, and said first spring being adjustable to determine the condition to which said switch will respond.
11. In an automatically operable snap switch, a pair of switch contacts, one of said contacts being fixed, the other of said contacts being movable, a lever carrying said movable contact, an armature carried by said lever, a magnet for attracting said armature and operable to cause said switch to open and to close with a snap action, said magnet also functioning to hold said movable contact tensioned against said fixed contact when said switch is closed, a spring urging said lever in one direction, an adjustable abutment for adjusting the compression of said spring, a second spring urging said lever in the opposite direction, said second spring being alined with and diametrically opposed to said first spring and of substantially the same strength as said first spring, thermal expansion means for transmitting movement to said second spring and said lever, said thermal expansion means being operative to actuate said lever, and said first spring being adjustable to determine the temperature to which said switch will respond.
12. In an automatically operable snap switch, a pair of switch contacts, one of said contacts being fixed, the other of said contacts being movable, a lever carrying said movable contact, an armature carried by said lever, a magnet for attracting said armature and operable to cause said switch to open and to close with a snap action, said magnet also functioning to hold said movable contact tensioned against said fixed contact when said switch is closed, a spring urging said lever in one direction, an adjustable abutment for adjusting the compression of said spring, a plunger bearing against said lever in opposition to said spring, a metal bellows surrounding said plunger and affixed to said plunger at one end, said bellows functioning as a spring means in opposition to said first-named spring, a spring bearing against said plunger, an adjustable abutment for adjusting the compression of said second-named spring, said second-named spring being adjustable to determine the force counterbalancing said first-named spring; said plunger, said bellows, and said second-named spring being

aligned with and diametrically opposed to said first-named spring and exerting substantially the same force against said lever as said first-named spring; said plunger and bellows being responsive to the application of gaseous pressure thereto thereby to actuate said lever, and said first-named spring being adjustable to determine the pressure to which said switch will respond.

13. In an automatically operable snap switch, a pair of switch contacts, one of said contacts being movable, the other of said contacts being fixed, a lever, a resilient member carried by and affixed to said lever and carrying said movable contact, means carried by said lever and operable to tension said resilient member, means to adjust the tension of said resilient member, said tensioned resilient member being operable to prevent vibration on opening or closing of said switch, means to cause said switch to open and to close with a snap action, said last-named means also functioning to hold said movable contact tensioned against said fixed contact when said switch is closed, spring means urging said lever in one direction, and means operable to urge said lever in the opposite direction.

14. In an automatically operable snap switch, a pair of switch contacts, one of said contacts being movable, the other of said contacts being fixed, a lever, a resilient member carried by and affixed to said lever and carrying said movable contact, means carried by said lever and operable to tension said resilient member, means to adjust the tension of said resilient member, said tensioned resilient member being operable to prevent vibration on opening or closing of said switch, means to cause said switch to open and to close with a snap action, said last-named means also functioning to hold said movable contact tensioned against said fixed contact when said switch is closed, spring means urging said lever in one direction, and means including pressure responsive means and a second spring means operable to urge said lever in the opposite direction.

15. In an automatically operable snap switch, a pair of switch contacts, one of said contacts being movable, the other of said contacts being fixed, a lever, a resilient member carried by and affixed to said lever and carrying said movable contact, means carried by said lever and operable to tension said resilient member, means to adjust the tension of said resilient member, said tensioned resilient member being operable to prevent vibration on opening or closing of said switch, means to cause said switch to open and to close with a snap action, said last-named means also functioning to hold said movable contact tensioned against said fixed contact when said switch is closed, spring means urging said lever in one direction, a second spring means operable to urge said lever in the opposite direction, and means responsive to the restricted movement of a liquid under pressure and operable to transmit force to said second spring means and said lever.

16. In an automatically operable snap switch, a pair of switch contacts, one of said contacts being fixed, the other of said contacts being movable, a lever, a resilient member carried by and affixed to said lever and carrying said movable contact, means carried by said lever and operable to tension said resilient member, means to adjust the tension of said resilient member, said tensioned resilient member being operable to prevent vibration on opening or closing of said switch, an armature carried by said lever, a mag-

net for attracting said armature and operable to cause said switch to open and to close with a snap action, said magnet also functioning to hold said movable contact tensioned against said fixed contact when said switch is closed, a spring urging said lever in one direction, an adjustable abutment for adjusting the compression of said spring, a plunger bearing against said lever in opposition to said spring, a metal bellows surrounding said plunger and affixed to said plunger at one end, said bellows functioning as a spring in opposition to said spring, a spring bearing against said plunger, an adjustable abutment for adjusting the compression of said second spring, said second spring being adjustable to determine the tension against said first spring, said plunger and bellows being responsive to the application of gaseous pressure thereto thereby to actuate said lever, and said first spring being adjustable to determine the pressure to which said switch will respond.

17. In an automatically operable snap switch, a pair of switch contacts, one of said contacts being fixed, the other of said contacts being movable, a lever, a resilient member carried by and affixed to said lever and carrying said movable contact, means carried by said lever and operable to tension said resilient member, means to adjust the tension of said resilient member, said tensioned resilient member being operable to prevent vibration on opening or closing of said switch, means operable to cause said switch to open and to close with a snap action, a spring urging said lever in one direction, an adjustable abutment for adjusting the compression of said spring, a plunger bearing against said lever in opposition to said spring, a metal bellows surrounding said plunger and affixed to said plunger at one end, said bellows functioning as a spring in opposition to said spring, a spring bearing against said plunger, and adjustable abutment for adjusting the compression of said second spring, said second spring being adjustable to determine the tension against said first spring, said plunger and bellows being responsive to the application of gaseous pressure thereto thereby to actuate said lever, and said first spring being adjustable to determine the pressure to which said switch will respond.

18. In an automatically operable snap switch, a pair of switch contacts, one of said contacts being fixed, the other of said contacts being movable, a lever, a resilient member carried by and affixed to said lever and carrying said movable contact, means carried by said lever and operable to tension said resilient member, means to adjust the tension of said resilient member, said tensioned resilient member being operable to prevent vibration on opening or closing of said switch, an armature carried by said lever, a magnet for attracting said armature and operable to cause said switch to open and to close with a snap action, said magnet also functioning to hold said movable contact tensioned against said fixed contact when said switch is closed, a spring urging said lever in one direction, an adjustable abutment for adjusting the compression of said spring, a second spring urging said lever in the opposite direction, said second spring being aligned with and diametrically opposed to said first spring and of substantially the same strength as said first spring, liquid pressure expansive means for transmitting movement to said second spring and said lever, a plunger operatively connecting said liquid pressure ex-

pansive means and said second spring, said liquid pressure expansive means being operative to actuate said lever, and said first spring being adjustable to determine the condition to which said switch will respond.

19. In an automatically operable snap switch, a pair of switch contacts, one of said contacts being fixed, the other of said contacts being movable, a lever, a resilient member carried by and affixed to said lever and carrying said movable contact, means carried by said lever and operable to tension said resilient member, means to adjust the tension of said resilient member, said tensioned resilient member being operable to prevent vibration on opening or closing of said switch, an armature carried by said lever, a magnet for attracting said armature and operable to cause said switch to open and to close with a snap action, said magnet also functioning to hold said movable contact tensioned against said fixed contact when said switch is closed, a spring urging said lever in one direction, an adjustable abutment for adjusting the compression of said spring, a plunger bearing against said lever in opposition to said spring, a metal bellows surrounding said plunger and affixed to said plunger at one end, said bellows functioning as a spring means in opposition to said first-named spring, a spring bearing against said plunger, an adjustable abutment for adjusting the compression of said second-named spring, said second-named spring being adjustable to determine the force counterbalancing said first-named spring; said plunger, said bellows, and said second-named spring being alined with and diametrically opposed to said first-named spring and exerting substantially the same force against said lever as said first spring; said plunger and bellows being responsive to the application of gaseous pressure thereto thereby to actuate said lever, and said first spring being adjustable to determine the pressure to which said switch will respond.

20. In an automatically operable snap switch, two pairs of switch contacts, two of said contacts being fixed, the other two of said contacts being movable, a lever carrying said movable contacts, said lever being of an insulating material, bifurcated at one end and trifurcated at the other end, a metal U shaped flanged portion partially covering and enclosing the bifurcated end of said lever, said lever being fulcrumed on said metal flange portion and shiftable slightly laterally, a casing enclosing said contacts and said lever and carrying the fulcrum for said lever, a U shaped resilient strip of metal carried by the outer prongs of said trifurcated end portion and carrying said movable contacts, a member having an upturned end portion carried by and affixed to the underside of each of outer prongs of said trifurcated end portion, said upturned end portions having an aperture therethrough receiving the end portion of said resilient metal strips, an adjustment member extending through said member into said outer prongs whereby said member may be adjusted as to tension said resilient metal strip, a magnetic armature carried by the center prong of said trifurcated end portion, a magnet for attracting said armature, said magnet being operable to cause said switch contacts to open and to close with a snap action, said magnet being further operable to cause said movable contacts to be tensioned against said fixed contacts when said switch contacts are closed, an adjustable abutment carrying said magnet, said magnet being adjustable as to vary the tension of the contacts when closed and to vary the amount of travel of the means operating said lever necessary to cause said contacts to snap open or to snap closed, a swivel member carried between the prongs of said trifurcated

end portion, a spring positioned against said swivel member and urging said lever in one direction, an adjustable abutment for adjusting the compression of said spring, a plunger positioned against said swivel member in opposition to said spring, a metal bellows surrounding said plunger and affixed to one end thereof, said bellows functioning as a spring means in opposition to said spring and urging said lever in the opposite direction, a spring bearing against said plunger, an adjustable abutment for adjusting the compression of said second-named spring, said second-named spring being adjustable to determine the initial force exerted against said first spring; said plunger, said bellows, and said second-named spring being alined with and diametrically opposed to said first-named spring and exerting substantially the same force against said swivel member as said first spring thereby functioning to center said lever on its fulcrum so as to reduce side friction between said lever and said casing, said plunger and bellows being responsive to the application of gaseous pressure thereto thereby to actuate said lever, an adjustable abutment carrying said magnet, said magnet being adjustable as to vary the tension of the contacts when closed and to vary the amount of travel of said plunger necessary to cause said contacts to snap open or to snap closed, and said first spring being adjustable to determine the pressure to which said switch will respond.

21. In an automatically operable snap switch, two pair of switch contacts, two of said contacts being fixed, the other two of said contacts being movable, a lever carrying said movable contacts, said lever being of an insulating material, bifurcated at one end and trifurcated at the other end, a metal U shaped flanged portion partially covering and enclosing the bifurcated end of said lever, said lever being fulcrumed on said metal flange portion and shiftable slightly laterally, a casing enclosing said lever and said contacts and carrying the fulcrum of said lever, a U shaped resilient strip of metal carried by the outer prongs of said trifurcated end portion and carrying said movable contacts, a member having an upturned end portion carried by and affixed to the underside of each of outer prongs of said trifurcated end portion, said upturned end portions having an aperture therethrough receiving the end portion of said resilient metal strips, an adjustment member extending through said member into said outer prongs whereby said member may be adjusted as to tension said resilient metal strip, a magnetic armature carried by the center prong of said trifurcated end portion, a magnet for attracting said armature, said magnet being operable to cause said switch contacts to open and to close with a snap action, said magnet being further operable to cause said movable contacts to be tensioned against said fixed contacts when said switch contacts are closed, an adjustable abutment carrying said magnet, said magnet being adjustable as to vary the tension of the contacts when closed and to vary the amount of travel of the means operating said lever necessary to cause said contacts to snap open or to snap closed, a swivel member carried between the prongs of said trifurcated end portion, a spring positioned against said swivel member and urging said lever in one direction, an adjustable abutment for adjusting the compression of said spring, a second spring positioned

against said swivel member in opposition to said first-named spring and urging said lever in the opposite direction, said second spring being alined with and diametrically opposed to said first-named spring and of substantially the same strength as said first-named spring, said first-named and said second springs functioning to center said lever on its fulcrum thereby to reduce side friction between said lever and said casing, fluid expansion means for transmitting movement through said second spring to said lever thereby to actuate said lever and said switch, a plunger operatively connecting said fluid expansion means and said second spring, and said first-named spring being adjustable to determine the condition to which said switch will respond.

22. In an automatically operable snap switch, two pairs of switch contacts, two of said contacts being fixed, the other two of said contacts being movable, a lever carrying said movable contacts, said lever being of an insulating material, bifurcated at one end and trifurcated at the other end, a metal U shaped flanged portion partially covering and enclosing the bifurcated end of said lever, said lever being fulcrumed on said metal flange portion and shiftable slightly laterally, a casing enclosing said contacts and said lever and carrying the fulcrum for said lever, a U shaped resilient strip of metal carried by the outer prongs of said trifurcated end portion and carrying said movable contacts, a member having an upturned end portion carried by and affixed to the underside of each of outer prongs of said trifurcated end portion, said upturned end portions having an aperture therethrough receiving the end portion of said resilient metal strips, an adjustment member extending through said member into said outer prongs whereby said member may be adjusted as to tension said resilient metal strip, a magnetic armature carried by the center prong of said trifurcated end portion, a magnet for attracting said armature, said magnet being operable to cause said switch contacts to open and to close with a snap action, said magnet being further operable to cause said movable contacts to be tensioned against said fixed contacts when said switch contacts are closed, and adjustable abutment carrying said magnet, said magnet being adjustable as to vary the tension of the contacts when closed and to vary the amount of travel of the means operating said lever necessary to cause said contacts to snap open or to snap closed, a swivel member carried between the prongs of said bifurcated end portion, a spring positioned against said swivel member and urging said lever in one direction, an adjustable abutment for adjusting the compression of said spring, a plunger positioned against said swivel member in opposition to said spring, a metal bellows surrounding said plunger and affixed to one end thereof, said bellows functioning as a spring means in opposition to said spring and urging said lever in the opposite direction, said bellows being thermo-responsive to the expansion and contraction of a thermostatic fluid contained therewithin, a supporting member for said spring, a lever arm engaging said supporting member and operable upon movement to control the compression of said spring, a second lever arm for operating said first-named lever arm and including a member for transmitting thrust therebetween, an adjustable screw abutment cooperable with said second lever arm and operable to adjust the same, and said adjustable

screw abutment being operable through said first-named lever arm, said thrust member, and said second lever arm to determine the compression of said spring thereby to determine the temperature to which said bellows and said switch will respond.

23. In a device of the character described, a lever shiftable slightly laterally on its fulcrum, supporting means for said lever, a pivoted swivel member carried by said lever, a spring engaging said pivoted swivel member and operable to urge said lever in one direction, an adjustment member engaging said spring and operable to determine the compression of said spring thereby determining the force required to move said lever in opposition to said spring, a second spring engaging said swivel member and alined with and diametrically opposed to said first-named spring, means for transmitting force to said second spring for moving said lever, and said first-named spring and said second spring being further operable to maintain said lever centered with respect to the line of thrust of said first-named and said second springs.

24. In a snap acting device, a lever adapted for snap movement, said lever being limited in its range of movement, a pivoted member carried by said lever, a spring operatively engaging said pivoted member and urging said lever in one direction, means operatively engaging said pivoted member and urging said lever in the opposite direction, said last-named means being elastic in form, said spring and said elastic means being oppositely alined and operable to center said lever on its fulcrum, a magnet operable to cause said lever to move with a snap action when said lever is within a predetermined distance of one limit of its movement, the force exerted by said elastic means being of a predetermined value to move said lever to said predetermined distance against the opposition of said spring, snap movement of said lever being operable to cause the force exerted by said elastic means against said lever to decrease, the field of attraction of said magnet being such that as said lever moves from said predetermined distance to said one limit of movement the attractive force between said magnet and said lever increases more rapidly than the force exerted by said elastic means decreases, and said magnet being operable upon decrease of force exerted by said elastic means to hold said lever at said one limit of movement after the force exerted by said elastic means has decreased below said predetermined value until a second predetermined value is reached.

25. In a control device, a control means, a lever operable to move said means, means pivotally supporting said lever, a rockable abutment member, means carried by said lever adjacent said lever supporting means and pivotally supporting said abutment member for rocking movement on an axis parallel to the axis of movement of said lever, means operable to move said lever in one direction and acting on and in substantially balanced relation to the axis of movement of said abutment member, and an actuating means operable to move said lever in the opposite direction and acting on said abutment member in opposition to and in substantial alinement with the line of thrust of said operable means, said rockable abutment member maintaining the thrust of said operable means and of said actuating means in substantial alinement throughout the range of movement of said lever.

26. In an electric switch, an operating lever,

a U-shaped contact-carrying member of resilient sheet material in overlying substantially parallel spaced relation to one end of said lever, means securing the base portion of said member to one side of said lever, the legs of said contact-carrying member extending beyond the end of said lever, and a vibration snubbing resilient sheet material member of U-shaped form in substantial registry with said contact-carrying member, means securing the base portion of said snubbing member to the other side of said lever, the free ends of said snubbing member being spaced from said lever for movement and having apertured end portions extending beyond the end of said lever and receiving and confining the free end portions of said contact carrying member.

27. In an electric switch, an operating lever, a U-shaped contact-carrying member of resilient material in overlying substantially parallel spaced relation to one end of said lever, means securing the base portion of said member to one side of said lever, the legs of said contact-carrying member extending beyond the end of said lever, a vibration snubbing resilient member of U shaped form in substantial registry with said contact-carrying member, means securing the base portion of said snubbing member to the other side of said lever, the free ends of said snubbing member being spaced from said lever for movement and having apertured end portions extending beyond the end of said lever and receiving and confining the free end portions of said contact carrying member, a magnetic armature positioned between the legs of said contact-carrying member and carried by said lever, and a magnet adjustably positioned above said armature so that when said lever has moved a predetermined distance toward said magnet the magnetic attraction between said magnet and said armature will cause said lever to move with a snap action.

28. In an electric switch, a casing having upper, lower, and side walls, an operating lever fulcrumed on said side walls and movable between predetermined limits, a U shaped contact-carrying member of resilient material in overlying substantially parallel spaced relation to one end of said lever, means securing the base portion of said member to one side of said lever, the legs of said contact-carrying member extending beyond the end of said lever, a vibration snubbing resilient member of U shaped form in substantial registry with said contact-carrying member, means securing the base portion of said snubbing member to the other side of said lever, the free ends of said snubbing member being spaced from said lever for movement and having apertured end portions extending beyond the end of said lever and receiving and confining the free end portions of said contact carrying member, a magnetic armature positioned between the legs of said contact-carrying member and car-

ried by said lever, a magnet adjustably carried by said upper wall above said armature so that when said lever has moved a predetermined distance toward said magnet the magnetic attraction between said magnet and said armature will cause said lever to move with a snap action, and a bracket member carried by said upper wall and cooperatively engaging the free end portion of said lever and operable as a stop means for limiting the range of movement of said lever.

5 29. In a device of the character described, a lever, actuating means operable to move said lever, elastic means operable to transmit the force of said actuating means to said lever, and means determining the extent of stress in said elastic means necessary to move said lever, said last-named means including a spring aligned with and opposed to said elastic means and cooperable therewith to maintain said lever centered upon its fulcrum, and means to adjust the compression of said spring.

10 30. In a device of the character described, a lever, an expansible incompressible means operable to move said lever, a spring for transmitting force from said expansible means to said lever, a second spring aligned with and opposed to said first-named spring, an adjustment member for said second spring, and said second spring being adjustable to determine the amount of expansion of said expansible means necessary to move said lever.

15 31. In an electric switch, an operating lever, a U shaped contact carrying member of resilient material in overlying substantially parallel spaced relation to one end of said lever, a pivoted member carried by said lever, elastic operating means engageable with one side of said pivoted member for moving said lever, a spring oppositely aligned with the point of engagement of said operating means and engaging the other side of said pivoted member to resist movement of said lever, a magnetic armature carried by said lever, and a magnet adjustably positioned above said armature so that when said lever has moved a predetermined distance toward said magnet the magnetic attraction between said magnet and said armature will cause said lever to move with a snap action.

20 40 50 EARNEST J. DILLMAN.
